CLAIM

The ornamental design for a combined window frame lineal and screw boss, as shown and described.

DESCRIPTION

Related to application Ser. No. 29/691,696, filed concurrently.

FIG. 1 is a perspective view of a combined window frame lineal and screw boss, showing my new design;

FIG. 2 is a right end view thereof;

FIG. 3 is a top view thereof;

FIG. 4 is a front view thereof, the opposing rear view being a mirror image thereof;

FIG. 5 is a top view thereof; and,

FIG. 6 is a bottom view thereof.

The surface shading in the figures is fragmentarily shown for convenience of illustration, it being understood that the shading pattern is uniformly continued over the surface on which it appears.

The combined window frame and screw boss is shown with a symbolic break in its length. The appearance of any portion of the combined window frame lineal and screw boss between the break lines forms no part of the claimed design.
